ATTORNEY

UNITED STATES PATENT OFFICE.

SIMON B. HUNT, OF NEW YORK, N. Y.

PNEUMATIC APPARATUS FOR ECONOMIZING COMPRESSED AIR.

SPECIFICATION forming part of Letters Patent No. 223,649, dated January 20, 1880.

Application filed July 25, 1879.

To all whom it may concern:

Be it known that I, SIMON BENTON HUNT, of the city of New York, in the county of New York and State of New York, have invented 5 certain new and useful Improvements in Pneumatic Economizers in the Compression of and Expansion of Atmospheric Air for Ice-Making or Refrigerating Purposes; and I do hereby declare that the following is a full, clear, and 10 exact description of the invention, which will enable others skilled in the art to which it appertains to make and use the same, reference being had to the accompanying drawings, and to letters of reference marked thereon, which 15 form a part of this specification.

This invention relates to that kind of mechanical construction employed in the manufacture of ice and for refrigerating purposes, so that the elastic fluid passes into the expanding-engine from the compressor, so that a great 20 amount of elastic force is produced upon the piston-head in said engine to assist the working steam-engine to operate the several parts of the apparatus.

25 My improvement consists in so manipulating the compressed atmospheric air while in the expanding-cylinder that the greatest force is exerted upon the piston-head in said cylinder at any desired point of the steam-piston rod in 30 the cylinder—for instance, while it is forcing the pistons of the compressors to their most extreme point of pressure.

Referring to the drawings, Figure 1 is a plan view of my improved apparatus. Fig. 2 is a vertical section of the air-chest and valve-chamber D, forming a part of the expanding-engine. The steam-valves are shown at 1 2 3 4 operated by means of pedals 5 6 7 8 and shaft S, provided with pins a b c d. Said shaft S is operated by 40 the bevel-gearing o. (Shown at Fig. 1.) Fig.

3 is a side elevation of compressors B" B'", showing the connecting-pipes n n', to produce a vacuum to extract the warm air from the refrigerating-chamber or other use. Fig. 4 represents a working section, B", Fig. 3. 45

The piston in the expanding-cylinder C' may be adjusted to operate at any desirable point of the stroke of the steam-piston; also the pistons of the compressors B B'.

Referring to the valves, 1 and 3 operate together and 2 and 4 operate in a similar manner by means of the pedals 5 6 7 8, provided with pins a b c d, the whole being adjusted by the lever V, Fig. 1, acting upon the gate N to elevate or lower the valves 2 and 3, which control the air under pressure. 50 55

What I claim as novel and useful, and wish to protect by Letters Patent of the United States, is—

The steam-piston rod W, geared to the outer face of the fly-wheel Y, and the piston-rod in compressing-cylinder C' to the outer face of the fly-wheel Y', in such a manner that the said piston operates alternately in opposite directions to the steam-piston in cylinder A', by 60 which means the compressed air in the cylinder C' assists in operating the driving crank-shaft F, which operates the compressors B B', in combination with the valves 1 2 3 4, pedals 5 6 7 8, shaft-pins a b c d, and lever V, all constructed, arranged, and operating in the manner and for the purpose set forth. 65 70

In testimony that I claim the foregoing as my own invention I affix my signature in presence of two witnesses.

SIMON BENTON HUNT.

Witnesses:

E. CASADEVALL,
JAMES P. MCLEAN.
